UNITED STATES PATENT OFFICE

ARTHUR R. CURTIS, OF CLEVELAND, OHIO

SAFETY DEVICE FOR WASHING MACHINES

Application filed March 31, 1924. Serial No. 703,050.

This invention relates to safety devices for power operated washing machines of the rotary cylinder type and has for its object to provide means for preventing operation of the cylinder at times when parts thereof such as the lid are not properly positioned for operation, thereby avoiding injuries to the operator or to the machine, which might otherwise occur due to the starting of the driving mechanism with the parts of the cylinder improperly positioned.

In washing machines of the cylinder type injury to the cylinder and the tub or to the driving mechanism have frequently been occasioned by starting the operation of the cylinder with the lid thereof open or imperfectly secured causing the lid to become jammed between the body of the cylinder or the wall of the tub.

The present invention provides a control for the cylinder driving mechanism which is interposed between the driving mechanism and the lid of a cylinder and operates to prevent actuation of the cylinder at times when the lid of the cylinder is open.

With the above and other objects in view, the invention may be said to comprise the various modifications of the device illustrated in the accompanying drawing, hereinafter described and particularly set forth in the appended claims, together with such variations and modifications thereof as will be apparent to one skilled in the art to which the invention appertains.

Reference should be had to the accompanying drawings forming a part of this specification in which Fig. 1 is a fragmentary top plan view showing portions of the washing cylinder and of the tub in which it operates, together with the driving mechanism and controlling elements therefor interposed between the driving mechanism and the lid of the cylinder; Fig. 2 is a fragmentary sectional view showing the belt shifter and the automatically controlled locking device associated therewith in side elevation; Fig. 3 is a sectional view taken as indicated by line 3-3 in Fig. 2 looking in the direction indicated by the arrow; Fig. 4 is a fragmentary sectional view taken on an axial plane

through the free edge portion of the lid which forms a part of the cylindrical wall of the cylinder and showing the lid locking device and the controlling member mounted on one head of the cylinder which is actuated by the lid locking device; Fig. 5 is a fragmentary longitudinal section through the cylinder showing the latch bars and the operating pinion therefor in elevation; Fig. 6 is a fragmentary end elevation of the cylinder showing the actuating bar mounted thereon; Fig. 7 is a top plan view of the clip for releasably holding the bolt operating handle in locking position; Figs. 8 and 9 show a modified form of lid actuated controlling element on the cylinder, Fig. 8 being a fragmentary section on line 8-8 of Fig. 9, and Fig. 9 being a section on line 9-9 of Fig. 8; Fig. 10 is a sectional detail view showing a further modification of the means for actuating the controlling element from the lid.

Referring to the accompanying drawing Figs. 1 and 2 show an end wall of the tub 1 in which the washer cylinder is mounted, the cylinder 2 being mounted in horizontal position for rotation in the tub. The cylinder 2 is provided with a lid 3 which forms a portion of the cylindrical wall thereof and extends the full length of the cylinder, the lid 3 being secured along one longitudinal edge by a hinge 4 and being provided with locking bolts 5 which engage with the heads of the cylinder to secure the lid in closed position. The cylinder 2 has a perforated body preferably provided with reentrant portions 6 forming baffles, the opening closed by the lid 3 being adjacent one of the reentrant portions as shown in Figs. 1 and 6. The lid 3 is provided with inwardly extending flanges 7 along its opposite ends which fit closely within the heads of the cylinder and with an inwardly extending flange 8 along its free edge which extends into the adjacent reentrant portion 6 as shown in Fig. 6. A drive shaft 9 projects through one end wall of the tub and carries an enlarged head 10 inside the tub which is provided with spaced lugs 11 which engage in apertures in the head of the cylinder, the central portion of the cylinder head supported on the drive shaft 10.

being provided with a reenforcing plate 12. The specific structure and mounting of the washer cylinder per se forms no part of the present invention, the present invention, however, being shown as applied to a washer of the type disclosed in my co-pending application Serial No. 633,970, filed April 23, 1923.

Supported upon the frame work of the machine immediately outside the end wall of the tub 1 is a gear casing 13 through which the drive shaft 9 extends. Within the gear casing 13 there may be an automatic reversing mechanism such as commonly employed in washing machines of the cylinder type by means of which the cylinder is given a predetermined number of revolutions in one direction and then reversed and given the same number of revolutions in the opposite direction. The washer drive mechanism preferably includes a pair of worm gears 14 loosely mounted upon the shaft 9 and continuously driven in opposite directions by gearing from a pulley 15 which is arranged horizontally and has a vertical shaft extending into the casing and means may be provided for alternately clutching the worm gears 14 to the shaft to drive the cylinder alternately in opposite directions. The specific reversing gear employed is per se immaterial in so far as the present invention is concerned and the specific details thereof are not herein shown, the driving mechanism herein shown, however, being of the type disclosed in my co-pending application Serial No. 633,969, filed Apr. 23, 1923.

For stopping the cylinder with the lid at the top means are provided for disconnecting the washer drive gearing from the motor, the worm gearing through which the cylinder is driven providing a lock for retaining the cylinder in the position in which it is stopped so that the cylinder is rigidly held while the clothes are being inserted in or removed from the cylinder.

For connecting and disconnecting the motor I have provided a belt tightening pulley 19 which is attached to an arm 20 of a bell crank lever, the other arm 21 of which forms an outwardly projecting handle. In order to retain the tightener pulley 19 in belt tightening position and to hold it against vibration while in such position, the handle 21 carries a cam portion 22 which is engaged by a spring pressed plunger 23, the plunger 23 acting upon the inclined surface of the cam serving to exert a continuous inward pressure on the tightener pulley. In order to obtain quick and positive disengagement of the driving connection, means are provided in connection with the belt whereby the belt is shifted and held out of engagement with the driving pulley upon movement of the tightener pulley to releasing position. The releasing means consists of an arcuate guard 24 closely overlying the periphery of the

pulley 15 and inclined belt retaining member 25 adjacent the drive pulleys 17. Upon release of the belt by outward movement of the pulley 19, the portion of the belt passing around the pulley 17 is thrown outwardly and held in engagement with the retaining members 25. The belt drive herein shown is fully described and claimed in my co-pending application Serial No. 633,972, filed Apr. 23, 1923. It is to be understood that the washing machine above described is illustrative, merely, of the type of machine to which the present invention may be applied and that the structural and mechanical details thereof may be varied greatly in so far as the present invention is concerned.

The present invention consists in an attachment adapted to be applied to a washing machine of the general character above described which will serve to prevent the starting of the cylinder until the lid thereof has been properly positioned for operation and as herein shown consists of a locking device cooperating with a member which controls the driving mechanism, in this instance the belt tightener lever, the locking device having operating connections extending to the lid of the cylinder which so control the action of the locking device that the belt tightener lever will be held against movement toward tightening position until the lid of the cylinder has been properly closed. The cam portion 22 of the lever 21 is provided with an abutment 26 adapted to be engaged by the lower end of a dog 27 which is pivoted intermediate its ends at 28 and is engaged at its upper end by an arm 29 which is rigidly attached to a rod 30 which is slidably mounted within the tubular drive shaft 9, the outer end of the rod 30 projecting through the outer wall of the casing 13 and the arm 29 being secured thereto outside the casing. The inner end of the rod 30 in one position extends beyond the inner end of the shaft 9 and is pressed inwardly by a spring 31 connected to the arm 29 and to the casing 13. The rod 30 is urged by the spring 31 toward its innermost position in which its inner end projects into an aperture 32 at the center of the reenforcing plate 12 and engages the head of the cylinder. When the rod 30 and arm 29 are in their innermost positions, the dog 27 is held in position for engagement with the abutment 26 of the handle 21 but if the rod 30 and arm 29 be moved outwardly in opposition to the spring 31, the lower end of the dog 27 will be swung upwardly to clear the abutment 26 of the handle 21 so that the movement of the belt tightener is not interfered with.

To enable the locking dog to be controlled from the lid, means are provided on the cylinder for shifting the rod 30 outwardly to move the dog to inoperative position when the lid is closed and locked so that operation

of the cylinder is prevented while the lid thereof is opened. An actuating bar 33 is slidably mounted upon the head of the cylinder and is so positioned that its inner end is at substantially the axis of the cylinder, the inner end 34 of the bar 33 being bent inwardly into the aperture 32 of the plate 12 to provide an inclined end portion which is engageable with the rounded inner end of the rod 30 to shift the rod in opposition to the spring 31. The actuating bar 33 is slidably mounted in spaced clips 35 and 36 secured to the outer side of the cylinder head, the outer clip 36 forming a housing in which is located a coil spring 37 connected to the clip and to the bar 33 and acting to shift the bar 33 outwardly to a position in which its inner end 34 is out of engagement with the rod 30. The outer end of the bar 33 is bent inwardly at an angle to provide an inclined face 38 adapted to be engaged by an inclined face 39 at the end of one of the locking bolts 5 when moved to locking position through the apertures 40 in the heads of the cylinder. The bar 33 is normally held by the spring 37 in a position in which its upper end extends partially across the aperture 40 so that when the locking bolt is pushed through the aperture, the outer end of the bar is engaged by the inclined face 39 of the bolt forcing the bar inwardly to a position in which the inner end thereof engages and holds the rod 30 in its outermost position thereby holding the dog 27 in inoperative position. During the inward movement of the actuating bar 33, the inclined inner end 34 thereof engages the rounded inner end of the rod 30 causing the rod 30 to ride up the inclined end 34 onto the flat outer surface of the bar 33. Thus when the lid of the cylinder is closed and locked, the belt tightener is released permitting operative connection to be made between the motor and the cylinder to operate the cylinder. The spring 31 acts to press the rounded end of the rod 30 against the face of the bar 33 when the bar is shifted to its innermost position by the closing and locking of the cylinder lids. In order to prevent wear on the bar 33 by the pointed end of the rod 30 during rotation of the cylinder, means may be provided for relieving the pressure on the bar 33 during rotation of the cylinder. To accomplish this the lower end portion of the dog 27 as shown herein is provided with a bearing surface 27^a which engages with a raised edge portion 22^a of the cam 22 whenever the handle 21 is moved to belt tightening position causing the dog 27 to be shifted slightly in a direction to move the rod 30 outwardly out of contact with the bar 33 so that during operation of the cylinder the rod 30 will be out of contact with the bar 33.

The locking bolts 5 are extended and retracted by means of a pinion 41 which engages racks formed on the inner ends of the

bars, the pinion 41 being fixed to a shaft which extends through the lid and has a handle 42 attached thereto outside the lid. The handle 42 lies parallel with and closely adjacent the outer surface of the lid and means is provided for yieldingly holding the handle in a position in which the bolts are extended to locking position so that the bolts cannot move to releasing position during operation of the cylinder. The yielding retainer for the handle 42 consists of a sheet metal clip 43 which is arched transversely at its ends and is secured to the lid beneath the handle 42. The clip 43 extends lengthwise of the lid and is provided with a pair of integral tongues 44 struck from the center thereof and lying flat against the lid, the tongues 44 being connected by rivets 45 to the lid. Beyond the ends of the tongues 44 the arched ends of the clip are provided with longitudinally extending grooves 46 adapted to receive the longitudinally disposed edges of the handle 42 when the handle is turned to locking position parallel with the free edge of the lid. The clip being made of resilient sheet metal, the arched end portions will spring sufficiently to permit the ends of the handle to ride over the ends of the clip into the grooves 46.

Various devices may be employed for actuating the lock controlling rod 30 from the lid of the cylinder. In Figs. 8 and 9 I have shown a modified form of attachment on the cylinder in which the actuating bar 33^a, which cooperates with the rod 30 in the same manner as the bar 33 in the modification first described, is actuated by means of a cam which is rigidly attached to one of the end flanges 7 of the lid 3 adjacent the hinge 4. The cam is in the form of a sheet metal clip 47 which lies closely adjacent and inside the head of the cylinder. The clip 47 is provided with a curved cam slot 48 which receives a pin 49 which is attached to the outer end of the bar 33^a and extends through a slot 50 in the head of the cylinder. The cam slot 48 is so formed that as the lid 3 is swung to open position, the bar 33^a is moved outwardly out of engagement with the rod 30 to permit the locking device to engage the handle of the tightener. When the lid 3 is moved to closed position the bar 33^a is shifted inwardly moving the rod 30 outwardly and rendering the locking device inoperative.

In Fig. 10 of the drawing I have shown a different method of actuating the actuating bar on the head of the cylinder from the lid. In this modification the upper end 51 of the actuating bar 33^b is bent inwardly and extends through a slot 52 in the head of the cylinder, the inturned end 51 being in a position to be engaged by the end flange 7 of the lid 3 when the lid is moved to closed position. For moving the actuating bar 33^b outwardly when the lid is opened a coil spring 53 is connected at its inner end to a lug 54 projecting

outwardly from the bar 33^b and at its outer end to the outwardly projecting flange 55 of the cylinder head.

Having described my invention, I claim:

5 1. In a machine of the character described, the combination with a rotatably mounted container, of driving mechanism therefor, a movable means for controlling said driving mechanism, and means including a shiftable member on said container adapted to lock said movable means to prevent actuation of said container by said driving mechanism.

10 2. In a machine of the character described, the combination with a rotatably mounted container, of driving mechanism therefor, movable means for connecting and disconnecting the driving mechanism and container, and means including a shiftable member on said container for locking said movable means against movement to connect said driving mechanism and container.

15 3. In a machine of the character described, the combination with a support having a container rotatably mounted thereon, of driving mechanism for the container, and means for controlling the operation of the driving mechanism, means for locking said controlling means to prevent rotation of said container, and a shiftable member on said container adapted to actuate said locking means.

20 4. In a machine of the character described, the combination with a rotatably mounted container, of driving mechanism therefor, manually operable means for controlling the driving mechanism to start and stop the rotation of said container, and a shiftable member on said container controlling the operation of said means for starting the rotation of said container.

25 5. In a machine of the character described, the combination with a rotatably mounted container having a lid thereon, of mechanism including worm gearing for rotating the container and means interposed between the lid of the container and the driving mechanism to prevent actuation of the worm gearing when the lid is open.

30 6. In a machine of the character described, the combination with a rotatably mounted container having a lid thereon, of mechanism for rotating the container including driving elements adapted to be disconnected to stop the container, means for shifting one of said driving elements out of engagement with the other, and means interposed between the lid of the container and one of the said driving elements to lock said driving element in disengaged position when the lid is open.

35 7. In a machine of the character described, the combination with a rotatably mounted container having a lid thereon, of driving mechanism for rotating the container, a manually operable controller for the driving mechanism by means of which the rotation of the container may be started or stopped and

means interposed between the lid of the container and the controller to restrain movement of the controller to start the rotation of the container when the lid is open.

40 8. In a machine of the character described, the combination with a support having a rotatably mounted container thereon, said container having a lid connected thereto, driving mechanism for rotating the container, shiftable controlling elements on the container and support, the shifting movement of the controlling element on the container being controlled by the lid and the controlling element on the support being operable manually to connect and disconnect said driving mechanism and container, and means operated by the controlling element on the container for locking the controlling element on the support.

45 9. In a washing machine, the combination with a horizontally disposed rotatable cylinder having an opening in its cylindrical wall and a lid for the opening adapted to be secured thereto to close the opening, of mechanism for rotating the cylinder, a manually operable controller for said mechanism, and means interposed between the controller and lid for locking the controller when the lid is open.

50 10. In a washing machine, the combination with a horizontally disposed rotatable cylinder having an opening in its cylindrical wall and a closure member adapted to be secured thereto to close the opening, of mechanism for rotating said cylinder alternately in opposite directions, means for starting and stopping said mechanism, and means interposed between said starting and stopping means and said lid to lock said starting means when the lid is open.

55 11. In a washing machine, the combination with a horizontally disposed rotatably mounted cylinder having an opening in its cylindrical wall, a lid for said opening, means for locking said lid in closed position, mechanism for rotating said cylinder, and means interposed between said locking means and mechanism for preventing operation thereof when the lid is unlocked.

60 12. In a washing machine, the combination with a rotatably mounted horizontally disposed cylinder having an opening in its cylindrical wall and a lid having a lock for securing it to the cylinder to close the opening, of mechanism for rotating the cylinder, a manually operable controller for said mechanism, locking means for said controller, and means operated by the lid lock for controlling the controller lock.

65 13. In a washing machine, the combination with a rotatably mounted horizontally disposed cylinder having an opening in its cylindrical wall and a lid for closing said opening, of mechanism for rotating the cylinder, a manually operable controller for said

mechanism by means of which operation of the cylinder may be controlled, a restraining device for said controller, and a cam carried by said lid and adapted to actuate said restraining device.

5 14. In a machine of the class described, the combination with a support having a container rotatably mounted thereon, of driving mechanism for the container, and means for controlling the operation of the driving mechanism comprising a controlling element on the support and a shiftable member on the container adapted to actuate the controlling element, and means for maintaining the shiftable member and controlling element out of contact during rotation of the container by the driving mechanism.

10 15. In a machine of the character described, a rotatably mounted container having an opening and a lid for closing said opening, means for locking the lid in closed position, mechanism for rotating said container, and means interposed between said locking means and said mechanism for preventing rotation of the container by said mechanism when the lid is unlocked.

20 In testimony whereof, I hereunto affix my signature.
